FORGING APPARATUS

Charles A. Brauchler, Canton, Ohio

Application April 28, 1943, Serial No. 484,823

10 Claims. (Cl. 78—9)

The invention relates to forging apparatus and more particularly to an apparatus for press forging a cylinder head, or the like, to form a recess or cavity therein.

The invention is especially concerned with the production of cylinder heads for aircraft engines and the improved forging apparatus is illustrated and described as designed for producing such cylinder heads.

It has been general practice to cast these cylinder heads from aluminum alloys, such as duralumin, but owing to the rapid strides made in aircraft during the present war, the power output of aircraft engines is increasing to such extent that cast heads will not have sufficient strength to withstand much greater pressures than now generated in the cylinders.

Reluctant to increase the weight of the engines by making a more massive, cast cylinder head, aircraft engineers experimented with forged cylinder heads to replace the conventional cast head and it was found that a forged head would have many advantages over the cast cylinder head.

The increased tensile strength of the forged material, over that of cast material, resulted in a cylinder head of twice the strength with no increase in weight or size, and permitted increased power output, decreased fuel consumption and increased cooling effect.

Owing to the great number of hammer forging operations required to produce a cylinder head forging, the limited number of drop hammers in this country of sufficient size and weight for the purpose, the heavy demand upon drop hammers for producing many other forged articles for war use, and the fact that sufficient hammers to produce these forged cylinder heads in any considerable numbers could not be obtained for about two years, it was impossible to produce forged cylinder heads in this manner.

Applicant overcame this obstacle by developing a method of press forging the forged cylinder heads in two or three operations, as compared with the minimum of nine hammer operations, obtaining the advantages of the forged head without the use of drop hammers and with only a fraction of the time and labor required for drop forging.

Said method of press forging the cylinder heads forms the subject matter of a copending application for patent filed by applicant, and the present invention is concerned with the apparatus by means of which the final press forging operation of said method is accomplished.

The present invention contemplates an appa-

ratus comprising cylinder operated dies conforming to the outside contour of the forged head, and a cylinder operated plunger cooperating therewith for forming the combustion chamber recess in the head.

The invention further contemplates the provision of such an apparatus in which the head is press forged to finished shape in said cylinder operated dies and held therein while the plunger is operated to form the combustion chamber recess and extrude a skirt upon the cylinder head forging.

The object of the invention is to provide an apparatus comprising a fixed die and a cooperating movable die, shaped to conform to the outer contour of the cylinder head forging, a hydraulic cylinder for moving the movable die, and a plunger operated by a hydraulic cylinder located at a right angle to the die operating cylinder, for forming the combustion chamber recess in the cylinder head forging while the forging is held clamped under extreme pressure between said dies.

These objects, together with others which will be apparent from the drawings and following description, may be attained by constructing the improved apparatus in the manner illustrated in the accompanying drawings, in which—

Figure 1 is a vertical, longitudinal sectional view through the improved press forging apparatus, showing the parts in the operated position with the dies in closed position and the plunger extended into the dies;

Fig. 2, a fragmentary sectional view of a portion of the die operating cylinder and piston, showing the oil connection for raising the piston;

Fig. 3, a front elevation of the apparatus;

Fig. 4, a top plan view of the apparatus with parts broken in section to show the oil connection for withdrawing the plunger operating piston;

Fig. 5, a section taken on the line 5—5, Fig. 1;

Fig. 6, an enlarged vertical, longitudinal sectional view through the dies, showing a cylinder head forging held therein and the plunger in operated position to form the combustion chamber recess in the head and to extrude the skirt therefrom;

Fig. 7, a perspective view of the partly completed forging; and

Fig. 8, a similar view of the forging before the combustion chamber recess is formed therein and the skirt extruded therefrom.

Similar numerals refer to similar parts throughout the drawings.

In order to have a clear understanding of the purpose of the apparatus forming the subject matter of the present invention, the press forging method in which said apparatus is used will be briefly described.

A blank, in the form of a block or ingot of duralumin, or the like, of suitable size is first heated to forging temperature and then press forged in dies shaped to produce the partly completed forging indicated generally at 10 in Fig. 7 having the rocker boxes 11 formed thereon.

This partly completed product, at forging temperature, may then be placed in a second set of dies and press forged to the desired finished outer contour as indicated generally at 12 in Fig. 8, and this forging, at forging temperature, may be placed in an apparatus forming the subject matter of the present application and held in the dies thereof while the plunger of the apparatus is operated to form the combustion chamber recess and extrude a skirt upon the forged head.

Or, if desired, the partly completed product 10, shown in Fig. 7, heated to forging temperature, may be placed directly in the dies of the apparatus and press forged to finished shape therein and held by the dies while the plunger is operated to form the combustion chamber recess and extrude the skirt.

The improved apparatus includes a pair of hydraulic cylinders comprising the upright cylinder indicated generally at 13 and the horizontal cylinder indicated generally at 14, for operating the dies and plunger respectively, and will be later described. A ring 15, shouldered as at 16 is fitted within the open lower end of the cylinder 13, the shouldered portion of the ring being provided with an annular rib 17 received within the correspondingly shaped groove 18 in the lower end of the cylinder.

Screws 19 detachably connect the ring 15 to the cylinder 13. The piston or ram 20 is slidably mounted with the cylinder 13 and provided at its upper end with the annular shoulder or flange 21, slidably contacting the inner wall 22 of the cylinder, the remaining portion of the piston being reduced in diameter as at 23 and slidably engaging the inner surface of the ring 15.

For the purpose of preventing leakage of oil around the piston a stuffing box recess 24 is formed in the inner surface of the ring 15 to receive the packing 25 which is held in place as by the gland 26 attached to the ring 15 by the screws 27.

Fluid under pressure may be admitted to the upper end of the cylinder, as by the pipe 28, for driving the piston or ram downward and one or more fluid pipes 29 may extend through the ring 15 to admit fluid pressure against the underside of the shoulder 21 to drive the piston upward.

The horizontal cylinder 14 has a ring 30 mounted in its open end said ring being shouldered as at 31 and connected to the end of the cylinder as by screws 32. The ring 30 has an elongated, cylindric portion 30a surrounding the reduced portion 33 of the piston 34 and recessed as at 35 to provide a stuffing box within which is located packing material 36 held in place by the gland 37 which is connected to the end of the cylindric portion 32 of the ring as by screws 38.

The piston 34 is provided with the enlarged annular shoulder or flange 39 slidably fitting

within the inner wall 40 of the cylinder and overhanging the ring 30 as best shown in Figure 1.

The cylinder 14 is mounted upon the base plate 41 and is provided with the outturned flange 42 engaging the shoulder 43 at the rear end of the base plate 41. A block 44 is mounted upon the forward end portion of the base plate 41 and the lower or fixed die 45 is mounted upon said block.

The upright front plate 46 is provided with the dovetailed lower end 47 mounted in the dovetailed groove 48 formed in the base plate 41 and a wedge 49 may be provided for tightly holding the two plates together.

An upper plate 50, similar to the base plate 41 is provided at its rear end with a shoulder 51 engaging the annular flange 42 upon the cylinder 14 and is provided at its forward end with a dovetailed groove 52 which receives the dovetailed upper end portion 53 of the front plate 46, a wedge 54 being provided for holding said plates tightly together.

The upper cylinder 13 is connected to the apparatus by means of the upright side plates 55 having the angular shoulders 56 at their lower ends engaging beneath the corresponding shoulders 57 at the sides of the base plate 41 and provided with the dovetailed grooves 58 near their upper ends receiving the dovetailed flanges 59 upon the cylinder 13, wedges 60 being provided for tightly securing these parts together.

Blocks 61 may be provided between the ring 15 and the top plate 50 to properly space the cylinder 13 relative to the other parts of the apparatus. With this construction all of the parts are rigidly and securely locked together so as to resist the pressures developed in the cylinders which may vary from 1400 to 1700 tons in each cylinder.

The movable die 62, complementary to the fixed die 45, is carried by the piston 23, being connected to the lower end thereof as by the dovetailed rib 63 upon the die and the corresponding groove 64 in the piston, a wedge 65 being preferably provided for tightly securing the die upon the piston.

The plunger 66 is mounted upon the end of the piston 34 and cooperates with the dies 45 and 62 as will be later described. The front plate 46 is provided in its upper portion with an opening 67 through which the forging may be passed to place it in or remove it from the lower fixed die 45.

Oil under pressure may be admitted to the outer end of the cylinder 14, as by the pipe 68, and one or more oil pipes 69 may be located through the ring 30 for admitting oil under pressure to the opposite end of the cylinder for withdrawing the piston 34.

The fixed die 45 and movable die 62 have cavities 70 and 71 respectively formed therein conforming to the finished outer contour of the forging 12 as shown in Fig. 8 and also shaped to form the extruded neck 72 at the lower end of the forging as shown in Fig. 6. The plunger 66 has a rounded nose 73 shaped to form the combustion chamber recess 74 in the heated forging as shown in Fig. 6.

In operating the apparatus the forging 12, as shown in Fig. 8, may be heated to forging temperature and passed through the opening 67 and placed in the cavity 70 of the fixed lower die 45, the piston 23 then being moved downward so as to clamp the heated forging tightly be-

tween the dies 45 and 62, the cavities of which conform to the contour of the forging 12.

The piston 33 is then operated forcing the rounded nose 73 of the plunger 66 into the heated forging, forming the combustion chamber recess 74 therein, the metal extruded by this operation forming the skirt 72.

In this operation the only function of the dies 45 and 62 is to hold the heated forging rigidly in place while the plunger is operated to produce the combustion chamber recess and the skirt.

However, the manufacture of these press forged cylinder heads may be expedited by eliminating one step in the method, the partly completed forging 10, shown in Fig. 7, being heated to forging temperature and placed in the lower fixed die 45, the upper movable die 62 being then lowered, press forging the heated metal to the final forged contour and while the die still remains closed under the extreme pressure of the cylinder 13 the plunger 66 is operated to form the combustion chamber recess and extrude the skirt as above described.

I claim:

1. Apparatus including a fixed die, a movable die, said dies having complementary cavities, a cylinder, a fluid operated piston in said cylinder, means connecting the movable die to said piston, a second fluid operated cylinder located at an angle to the first mentioned cylinder, a piston in the second cylinder and a plunger on the second piston cooperating with the dies, a base plate and a top plate connected at their rear ends to the second cylinder, a front plate connected to the forward ends of the plates, and side plates connected at opposite ends to the first cylinder and to the base plate.

2. Apparatus including a fixed die, a movable die, said dies having complementary cavities, a cylinder, a fluid operated piston in said cylinder, means connecting the movable die to said piston, a second fluid operated cylinder located at an angle to the first mentioned cylinder, a piston in the second cylinder and a plunger on the second piston cooperating with the dies, a base plate and a top plate connected at their rear ends to the second cylinder, a front plate connected to the forward ends of the plates, and side plates connected at opposite ends to the first cylinder and to the base plate, there being an opening in the top plate through which the first piston is located and blocks clamped between the first cylinder and the top plate.

3. Apparatus including a fixed die, a movable die, said dies having complementary cavities, a cylinder, a fluid operated piston in said cylinder, means connecting the movable die to said piston, a second fluid operated cylinder located at an angle to the first mentioned cylinder, a piston in the second cylinder and a plunger on the second piston cooperating with the dies, a base plate and a top plate connected at their rear ends to the second cylinder, a front plate connected to the forward ends of the plates, and side plates connected at opposite ends to the first cylinder and to the base plate, there being an opening in the front plate through which work may be passed to the dies.

4. Apparatus including a fixed die, a movable die, said dies having complementary cavities, a cylinder, a fluid operated piston in said cylinder, means connecting the movable die to said piston, a second fluid operated cylinder located at an angle to the first mentioned cylinder, a piston in the second cylinder and a plunger on the sec-

ond piston cooperating with the dies, a base plate and a top plate connected at their rear ends to the second cylinder, a front plate connected to the forward ends of the plates, and side plates connected at opposite ends to the first cylinder and to the base plate, there being an opening in the top plate through which the first piston is located blocks clamped between the first cylinder and the top plate, and there being an opening in the front plate through which work may be passed to the dies.

5. Apparatus including a fixed die, a movable die, said dies having complementary cavities, a cylinder, a fluid operated piston in said cylinder, means connecting the movable die to said piston, a second fluid operated cylinder located at an angle to the first mentioned cylinder, a piston in the second cylinder, a plunger on the second piston cooperating with the dies, a base plate on which the fixed die is mounted, interlocking formations on the rear portion of the base plate and on the second cylinder, a front plate, interlocking formations upon the lower portion of the front plate and the forward portion of the base plate, a top plate, interlocking formations on the rear portion of the top plate and on the second cylinder, interlocking formations on the upper portion of the front plate and on the forward portion of the top plate, side plates, interlocking formations on the lower portions of the side plates and on the base plate and interlocking formations on the upper portions of the side plates and on the first cylinder.

6. Apparatus including a fixed die, a movable die, said dies having complementary cavities, a cylinder, a fluid operated piston in said cylinder, means connecting the movable die to said piston, a second fluid operated cylinder located at an angle to the first mentioned cylinder, a piston in the second cylinder, a plunger on the second piston cooperating with the dies, a base plate on which the fixed die is mounted, interlocking formations on the rear portion of the base plate and on the second cylinder, a front plate having an opening through which work may be passed to the dies, interlocking formations upon the lower portion of the front plate and the forward portion of the base plate, a top plate, interlocking formations on the rear portion of the top plate and on the second cylinder, interlocking formations on the upper portion of the front plate and on the forward portion of the top plate, side plates, interlocking formations on the lower portions of the side plates and on the base plate and interlocking formations on the upper portions of the side plates and on the first cylinder.

7. Apparatus including a fixed die, a movable die, said dies having complementary cavities, a cylinder, a fluid operated piston in said cylinder, means connecting the movable die to said piston, a second fluid operated cylinder located at an angle to the first mentioned cylinder, a piston in the second cylinder, a plunger on the second piston cooperating with the dies, a base plate on which the fixed die is mounted, interlocking formations on the rear portion of the base plate and on the second cylinder, a front plate, interlocking formations upon the lower portion of the front plate and the forward portion of the base plate, a top plate, interlocking formations on the rear portion of the top plate and on the second cylinder, interlocking formations on the upper portion of the front plate and on the forward portion of the top plate, side plates, interlocking formations on the lower portions of the side plates

and on the base plate and interlocking formations on the upper portions of the side plates and on the first cylinder, there being an opening in the top plate through which the first piston is located and blocks clamped between the first cylinder and the top plate.

8. Apparatus including a fixed die, a movable die, said dies having complementary cavities, a cylinder, dovetailed flanges on said cylinder, a fluid operated piston in said cylinder, means connecting the movable die to said piston, a second fluid operated cylinder located at an angle to the first mentioned cylinder, an outturned flange on the second cylinder, a piston in the second cylinder, a plunger on the second piston cooperating with the dies, a base plate on which the fixed die is mounted, a shoulder on the rear portion of the base plate interlocking with the flange on the second cylinder, a front plate having dovetailed upper and lower ends, there being a dovetailed groove in the front portion of the base plate receiving the dovetailed lower end of the front plate, a top plate having a shoulder interlocking with the flange upon the second cylinder and a dovetailed groove receiving the dovetailed upper end of the front plate, side plates having dovetailed grooves in their upper ends receiving the dovetailed flanges on the front cylinder and interlocking shoulders on the lower ends of the side plates and on the sides of the base plate.

9. Apparatus including a fixed die, a movable die, said dies having complementary cavities, a cylinder, dovetailed flanges on said cylinder, a fluid operated piston in said cylinder, means connecting the movable die to said piston, a second fluid operated cylinder located at an angle to the first mentioned cylinder, an outturned flange on the second cylinder, a piston in the second cylinder, a plunger on the second piston cooperating with the dies, a base plate on which the fixed die is mounted, a shoulder on the rear portion of the base plate interlocking with the flange on the second cylinder, a front plate having an opening

through which work may be passed to the dies and having dovetailed upper and lower ends, there being a dovetailed groove in the front portion of the base plate receiving the dovetailed lower end of the front plate, a top plate having a shoulder interlocking with the flange upon the second cylinder and a dovetailed groove receiving the dovetailed upper end of the front plate, side plates having dovetailed grooves in their upper ends receiving the dovetailed flanges on the front cylinder and interlocking shoulders on the lower ends of the side plates and on the sides of the base plate.

10. Apparatus including a fixed die, a movable die, said dies having complementary cavities, a cylinder, dovetailed flanges on said cylinder, a fluid operated piston in said cylinder, means connecting the movable die to said piston, a second fluid operated cylinder located at an angle to the first mentioned cylinder, an outturned flange on the second cylinder, a piston in the second cylinder, a plunger on the second piston cooperating with the dies, a base plate on which the fixed die is mounted, a shoulder on the rear portion of the base plate interlocking with the flange on the second cylinder, a front plate having dovetailed upper and lower ends, there being a dovetailed groove in the front portion of the base plate receiving the dovetailed lower end of the front plate, a top plate having a shoulder interlocking with the flange upon the second cylinder and a dovetailed groove receiving the dovetailed upper end of the front plate, side plates having dovetailed grooves in their upper ends receiving the dovetailed flanges on the front cylinder and interlocking shoulders on the lower ends of the side plates and on the sides of the base plate.
